United States Patent Office

Des. 202,749
Patented Nov. 2, 1965

202,749

AIRPLANE

Kenneth F. Holtby and Frederick A. Maxam, Bellevue,
and Maynard L. Pennell, Seattle, Wash., assignors to
The Boeing Company, Seattle, Wash., a corporation of
Delaware

Filed Mar. 19, 1965, Ser. No. 84,362

Term of patent 14 years

(Cl. D71—1)

Fig. 4

Fig. 5

FIGURE 1 is a front elevation view.

FIGURE 2 is a three-quarters front perspective view taken from the top.

FIGURE 3 is a three-quarters rear perspective view taken from the bottom.

FIGURE 4 is a side elevation view; and

FIGURE 5 is a top plan view of the new airplane design.

The dominant features of our design are shown in solid lines in the drawings.

We claim:

The ornamental design for an airplane, substantially as shown and described.
